SHIRT PACKAGING DEVICE

Tom A. Crossley, La Grange, Ga.

Application March 8, 1950, Serial No. 148,396

5 Claims. (Cl. 223—71)

1

This invention relates to packaging devices of the type employed by laundry establishments and has more particular reference to a packaging device for retaining collar-attached shirts in their freshly pressed condition during the normal handling and delivery to the customer.

One object of the invention is to provide an improved packaging device which will retain the body of the shirt and the collar in correctly fresh-pressed condition until used by the wearer.

Another object of the invention is to provide a packaging device, as characterized above, including a shirt reinforcing panel or backing panel, a collar protective panel connected to be spaced vertically above the backing panel, and a collar brace form connected to and cooperating with the collar protective panel to protect the collar and safeguard it from crushing.

Another object of the invention is to provide a packaging device, as characterized above, wherein the backing panel, the collar protective panel, and the collar brace form are cut from a single piece of sheet material.

Another object of the invention is to provide a packaging device, as characterized above, including an elongated narrow band connected to or formed integral with the collar brace form and adapted to be wrapped around the folded shirt with its free end secured by a board lock, or adhesively, to the backing panel at the point of connection of the back panel to the collar protective panel.

Another object of the invention is to provide a packaging device, as characterized above, which may be automatically opened by breaking the connection between the band and the backing panel and letting the shirt tumble until the shirt is free of the packaging device.

A further object of the invention is to provide a packaging device which is simple and inexpensive to manufacture, readily and easily folded and used in preparing the shirt for packaging, neat and attractive in appearance, and efficient in carrying out the purpose for which it is designed.

Other objects and advantages of the invention will appear in the following specification, when considered with the accompanying drawing, wherein:

Fig. 1 is a plan view of a packaging device embodying the invention;

Fig. 2 is a plan view showing a collar-attached shirt packaged in the packaging device shown in Fig. 1;

Fig. 3 is a vertical sectional view through the

2

packaging device, on the line 3—3 of Fig. 2; and

Fig. 4 is a fragmentary perspective view showing the manner in which the collar brace form is inserted in the shirt collar.

5 Referring now to the drawing, there is shown in Fig. 1, a packaging device 10 embodying the invention and comprising a reinforcing or backing panel 11, a connecting panel 12, a collar protective panel 13, a connecting panel 14, a collar brace form 15, and an elongated band 16.

The packing device may be made of any suitable material having the desired amount of stiffness and flexibility for the purpose, as for example, cardboard, and preferably is stamped or otherwise formed out of a single sheet of material.

The backing panel 11 is generally rectangular and is connected to the collar protective panel 13 by the rectangular connecting panel 12 which is connected to the backing panel 11 along a fold line 17 and to the collar protective panel along a fold line 18.

The collar protective panel 13 is a generally annular shaped member and is connected to the collar brace form 15 by a rectangular connecting tab or panel 14 which is connected to the collar protective panel along a fold line 19 and to the collar brace form along a fold line 20.

The collar brace form 15 is generally rectangular in outline and has curved generally parallel top and bottom edges 21, 22. The collar brace form is divided into upper and lower bracing panels 23, 24, respectively, by means of curved slots 25, 26 extending inwardly from the vertical side edges of the collar brace form. The slots 25, 26 are generally parallel with the curved upper and lower edges of the collar brace form.

The connecting tab or panel 14 is formed in the upper panel 23 of the collar brace form by spaced vertical slots 27 and 28, which extend inwardly from the upper edge 21, to the bottom fold line 20 of the tab.

A pair of wings or tabs 29, 30 are formed by means of converging slots 31 and 32 which extend downwardly and inwardly from the ends of the slots 25 and 26, respectively, and slots 33 and 34 which extend upwardly and inwardly from the ends of the slots 25 and 26, respectively. It should be noted that the slots 33 and 34 are curved to provide rounded ends 35 for the respective wings or tabs 29, 30.

The material between the inner ends of the slots 33 and 34 forms a panel connecting the upper and lower panels 23, 24 of the collar brace form and provides a straight fold line 36 about which the upper panel 23 is folded with respect to the lower panel 24. It

should be noted that the fold line 36 would be generally in line with the curved slots 25 and 26 if continued to a point of juncture. The wings or tabs 29, 30 are adapted to be folded outwardly about a fold line 37 extending between the inner adjacent ends of the slots 31, 32.

The elongated, narrow band 16 extends downwardly from the mid-portion of the bottom edge of the lower panel 24 of the collar brace form.

In Fig. 2 there is shown a shirt S, as completely and freshly ironed, and packaged in the packaging device shown in Fig. 1, ready for delivery to the customer. As there shown, the shirt S is of the well known collar-attached type and comprises a bosom portion, including both front and back portions of the shirt body, indicated generally at 38; and a collar 39 comprised of an inner fold 40 and an outer fold 41, terminating in open ends 42.

The reinforcing or backing panel 11 is positioned immediately beneath the bosom portion 38 of the shirt with the shirt tail and sleeves folded over it and with its upper end positioned below the upper end of the collar. The connecting panel 12 extends substantially vertically from the backing panel in engagement with the back of the collar. The collar protective panel 13 extends over the collar in general parallel relation with the backing panel 11. It should be noted that the collar protective panel is of a sufficient size to completely cover the upper edges of the collar. The upper panel 23 of the collar bracing form is folded down into the collar opening against the inner side walls of the inner fold 40 of the collar with the upper edge of the panel, after it has been folded down into the collar opening, barely clearing the top of the collar. The lower panel 24 of the collar bracing form is positioned between the inner fold 40 and the outer fold 41 of the collar with the wings or tabs 29, 30 extending laterally over the upper portion of the ends 42 of the collar to hold them in place. The elongated band 16 extends downwardly over the buttons on the shirt, around the bottom of the folded shirt, and has its free end secured to the connecting panel 12. It should be noted that the collar brace form braces the collar and prevents it from being crushed in handling or when one shirt is stacked on another. In this connection, it should be noted that the collar protective panel rests on the upper edge of the upper panel 23 of the collar brace form, after it has been inserted in the collar opening, and locks the collar brace form in place. The connecting panel 12 also helps to prevent crushing of the collar and helps to support the collar protective panel 13.

The packaging device 10 may be applied to package the shirt in any desired manner. Preferably, however, and particularly when employing a folding machine of the usual type, the packaging device is applied as follows:

With the freshly ironed, unfolded shirt lying collar up on the table, the lower panel 24 of the collar brace form is inserted between the inner fold 40 and the outer fold 41 of the collar, with the wings or tabs 29, 30 folding slightly upwardly about the fold line 37 and extending across the upper portion of the collar ends 42 (see Fig. 4). Then, the upper panel 23 of the collar brace form is folded about the fold line 36 down into the collar opening against the inner wall of the inner fold 40 of the collar, with the upper edge of the upper panel, after it has been folded down into the collar opening, barely

clearing the top of the collar. This requires that the connecting tab 14 be folded upwardly about its lower fold line 20, lifting the collar protective panel 13 vertically relative to the front of the shirt. Next, the collar protective panel 13 is folded about the upper fold line of the connecting tab 14 down over the top of the collar in substantially parallel relation with the front of the shirt. The collar protective panel will rest on the upper panel 23 of the collar brace form and lock the collar brace form in place. The elongated band 16 is left extending along the front of the shirt over the row of buttons thereon. Then, the connecting panel 12 is folded downwardly along the fold line 18 and the backing panel is folded along the fold line 17 to position it beneath the shirt in substantially parallel relation to the collar protective panel and the shirt is placed, collar down, on the platen of the folding machine, with the collar received in the usual collar receiving well thereof. In this connection, it should be pointed out that, as the collar protective panel extends only slightly over the upper edge of the collar, it will easily go down into the well of any of the usual types of folding machines. Then, the folding form of the machine is lowered onto the shirt and the backing panel and the sides of the shirt body, the sleeves, and the tail portion, are folded upwardly and inwardly onto the form in the usual manner. Next, the folding form is raised and the elongated strip 15 is folded around the bottom end of the folded shirt and up the back and adhesively secured to the connecting panel 12. The shirt is then removed from the folding machine and is packaged as shown in Fig. 2.

A shirt packaged with the packaging device of the invention may be automatically opened by a user by holding the shirt with the collar down and toward the holder over a bed or table and then breaking the connection between the band and the backing panel and letting the shirt tumble until it is free of the packaging device. The shirt will fall on the bed or table correctly placed before the holder, ready to be unbuttoned and put on.

While, in the particular embodiment of the invention illustrated, the packaging device has been shown as being cut or stamped from a single sheet of material, obviously, the several panels may be made of separate pieces suitably secured together, for example, the backing panel may be made separately and of heavier material than the remainder of the device. Obviously, too, the elongated band 16 may be wrapped around the body of the shirt in various ways and secured to the connecting panel 12, or it may be omitted, if desired.

From the foregoing, it readily will be seen that there has been provided an improved packaging device which will retain the body of the shirt and the collar in correctly fresh-pressed condition until used by the wearer, which protects the collar from being crushed or soiled, and is easily applied to a shirt and quickly removed therefrom, and which is simple and inexpensive to manufacture.

Obviously, the present invention is not restricted to the particular embodiment thereof herein shown and described; but is capable of various modifications within the scope of the appended claims.

What is claimed is:

1. A shirt packaging device for use in packing

collar-attached shirts, comprising a backing panel, around which the shirt is folded; a collar protective panel hingedly connected to said backing panel and adapted to overlie the shirt collar to protect it from soiling; and a collar brace form including a curved elongated, upper collar brace panel hingedly connected intermediate its ends to said collar protective panel and adapted to be folded down within the collar opening against the inner fold of the collar and under said collar protective panel, and an elongated lower collar brace panel hingedly connected intermediate its ends to said upper collar brace panel and adapted to have its ends inserted between the inner and outer folds of the shirt collar.

2. A shirt packaging device, as set forth in claim 1, including an elongated band connected at one end to said lower collar brace panel, said band being adapted to be wrapped around the folded shirt and have its free end secured to said backing panel.

3. A shirt packaging device, as set forth in claim 1, including a pair of opposed wing members extending upwardly and outwardly from the upper edge of said lower collar brace panel, said wing members being adapted to extend laterally over the free ends of the collar when said lower collar brace panel is inserted between the folds of the collar.

4. A blank adapted to be folded into a packaging device for laundered collar-attached shirts, comprising upper and lower elongated collar brace panels having arcuate longitudinal edges

with the mid-portion of the adjacent longitudinal edges of the panels hingedly connected together, the lower of said panels being adapted to have its free ends inserted in opposite directions between the folds of the shirt collar, the upper of said panels being adapted to be folded down inside the collar opening against the inner fold of the collar; a collar protective panel extending upward from and hingedly connected to the upper collar brace panel, said collar protective panel being adapted to be positioned over the collar to protect it and to lock the upper collar brace panel in its position inside the collar; and a backing panel extending upwardly from and hingedly connected to said collar protective panel and adapted to be positioned beneath the bosom of the shirt in substantial parallel relation to said collar protective panel.

5. A blank adapted to be folded into a packaging device, as set forth in claim 4, including an elongated band connected at one end to said lower collar brace panel, said band being adapted to be wrapped around the shirt and have its free end secured to said backing panel.
